(57) **CLAIM**

We claim the ornamental design for a dispenser with textured surface pattern, as shown and described.

DESCRIPTION

FIG. 1 is a perspective view of the dispenser of this invention, showing our new design for a dispenser with textured surface pattern comprising multiple bubble-like protrusions;

FIG. 2 is a front elevational view thereof;

FIG. 3 is a right side elevational view thereof;

FIG. 4 is a left side elevational view thereof;

FIG. 5 is rear elevational view thereof;

FIG. 6 is a top plan view thereof, showing a detachable panel, outlined by lines of perforation, which covers a dispensing opening for withdrawal of disposable sheet goods, such as paper towels;

FIG. 7 is a bottom plan view thereof; and,

FIG. 8 is a partial vertical cross-sectional view thereof, taken across a portion of the front wall of the dispenser.
